RETURN BEND FITTING

Fred C. Fantz, Webster Groves, Mo.

Application October 29, 1932, Serial No. 640,205

5 Claims. (Cl. 285—20)

My invention relates to that class of return bends for use in tube coils or banks in cracking stills and specifically to such as is described in my application for patent, Serial No. 585,220, now 5 Patent No. 1,936,386 of which this is a continuation in part and which is also covered by my Patent No. 1,752,331, in which the tube is demountable, the tubes having shoulders which engage sectional metal bushings mounted intermediate 10 the tube and the annular portions of the housing, thus permitting one tube to be removed for inspection or replacement, without having to disturb or destroy the adjacent tube.

It is well known in the industry that the return 15 bends have to be removed at periods of more or less duration to remove the coke which is deposited in the tubes during the operation as this is highly dangerous and if not removed is liable to cause a ruptured tube with attendant fire resulting in property damage and possible loss of life.

This is due to the fact that the coke acts as an insulator for the oil so that the metal forming the tube is not cooled by the passage of the oil and when the limit of endurance of the metal 25 is reached a disastrous accident may occur. It was for this reason that the fitting described in by patent was produced.

My present invention has for its object to provide a different form of sectional ring to engage 30 the shoulders upset on the tubes. In my present invention instead of a sectional ring, I employ a plate formed in two parts or halves each half of which is provided with portions having shoulders formed on them which are adapted to be locked 35 to the shoulders formed on the tubes adjacent their ends, means may be provided to secure the two halves together if desired.

My means of accomplishing the foregoing objects may be more readily understood by having 40 reference to the accompanying drawings which are hereunto annexed and made a part hereof, in which

Fig. 1 is a side elevation of my improvement, part of the walls of the housing being broken 45 away showing the parts in section;

Fig. 2 is a section in Fig. 1 on the line 2—2 the tubes being omitted;

Fig. 3 is a fragmentary detail view;

Fig. 4 is a view similar to Fig. 1 showing a 50 slightly different form of plate;

Fig. 5 is a section on the line 5—5 in Fig. 4; and

Fig. 6 is a fragmentary detail view.

Similar reference numerals refer to similar 55 parts throughout the entire description.

As shown in the drawings the tubes 1 and 2 are connected by a return bend 3 so as to provide an uninterrupted passageway therethrough. This bend is mounted in a housing which comprises annular portions 4 and 5 in which the tubes 1 and 2 are demountably mounted side walls, 7, 8, 9 and 10 extend upwardly from the annular portions 4 and 5 respectively. Toggles or strong backs 11 are mounted in slots 12 and 13 formed in the upwardly extending side walls. Set screws 14 are mounted in the toggles 11. The inner ends of these set screws 14 engage abutments formed on the external walls of the return bend 3. Preferably the inner walls of the annular portions are provided with shoulders 15 against which 15 shoulders 16 formed on the tube engaging portions of the plate rest. Shoulders 21 are formed on the arcuate surfaces of these portions against which the shoulders 17, formed by upsetting the tube ends, rest. This plate is preferably made 20 in two halves 18 and 19 which may be fastened together by a bolt 20 though obviously some other form of fastening may be used if desired. The tube engaging portions are preferably formed with extensions 22 and 23. By this construction, 25 instead of having a number of pieces of a section ring for each tube, a half of the plate serves the same purpose. In some instances it may be found desirable to form the plate as shown in Figs. 4 to 6 in which the extensions 22 and 23 are omitted 30 and the plate is just a flat piece of metal each half of which has a shoulder 21 to engage the shoulders 17 on the tubes. I have shown a type of joint for the tubes and the return bend which has been found in practice to be highly satisfactory, obviously any one type of joint may be employed.

From the foregoing description it clearly appears that by tightening the set screws 14 against the abutments on the return bend 3 that the annular portions of the housing will draw the ends of the tubes against the return bend and form a leak proof joint.

Having described my invention what I regard as new and desire to secure by Letters Patent is: 45

1. In a refinery apparatus, a return bend adapted to connect a pair of adjacent still tubes to provide an uninterrupted passageway therethrough, a housing in which said return bend is located, said housing comprising annular portions in which the ends of said tubes are demountably mounted, said tubes being enlarged adjacent their ends to form external shoulders, a spacing plate formed in halves having portions adapted to be locked to the shoulders on the tube 55

and means to hold said parts in assembled relation and form a leak proof joint.

2. In a refinery apparatus, a return bend adapted to connect a pair of adjacent still tubes, 5 to provide an uninterrupted passageway therethrough, a housing in which said return bend is located, said housing comprising annular portions in which the ends of said tubes are demountably mounted, shoulders on the inner walls 10 of said annular portions, said tubes being enlarged adjacent their ends to form external shoulders, a spacing plate formed in halves having portions adapted to be locked to the shoulders on the tube, said tube engaging portions resting 15 on the shoulder on the inner walls of said annular portions, and means to hold said parts in assembled relation and form a leakproof joint.
3. In a refinery apparatus, a return bend adapted to connect a pair of adjacent still tubes 20 to provide an uninterrupted passageway therethrough, a housing in which said return bend is located, said housing comprising annular portions in which the ends of said tubes are demountably mounted, shoulders on the inner walls of said 25 annular portions, said tubes being enlarged adjacent their ends to form external shoulders, a spacing plate formed in halves, having portions adapted to be locked to the shoulders on the tube, downwardly depending extensions on the 30 tube engaging portions of said plate, and means to hold said parts in assembled relation and form a leakproof joint.

4. In a refinery apparatus, a return bend adapted to connect a pair of adjacent still tubes to provide an uninterrupted passageway therethrough, a housing in which said return bend is located, said housing comprising annular portions in which the ends of said tubes are demountably mounted, said tubes being enlarged adjacent their ends to form external shoulders, a spacing plate formed in halves having portions adapted to be locked to the shoulders on the tube, means to secure said halves together, and means to hold said parts in assembled relation and form a leak proof joint. 5

5. In a refinery apparatus, a return bend adapted to connect a pair of adjacent still tubes 15 to provide an uninterrupted passageway therethrough, a housing in which said return bend is located, said housing comprising annular portions in which the ends of said tubes are demountably mounted, shoulders on the inner walls 20 of said annular portions, said tubes being enlarged adjacent their ends to form external shoulders, a spacing plate formed in halves having portions adapted to partially encircle a tube and to be locked to the shoulders on the tube, said 25 tube engaging portions resting on the shoulder on the inner walls of said annular portions, and means to hold said parts in assembled relation and form a leakproof joint.
